UNITED STATES PATENT OFFICE

2,480,632

HEADLIGHT

Jack Cathrill, San Francisco, Calif.

Application January 29, 1945, Serial No. 575,050

2 Claims. (Cl. 240—41.4)

1

This invention relates to head lights and particularly to a lens and reflector for head lights on automobiles and other types of vehicles and the like.

Among the objects of my invention is to construct a lens for head lights and reflector surfaces in such a manner that a relatively wide, sharply defined beam is issued through the lens resulting in lateral distribution of the light rays as well as downward illumination upon the ground in advance of the head light without any upward blinding rays of light.

Among the features of my invention are: a lens with a reflector placed within the lens by molding or otherwise for reflecting upward rays of light back to the parabolic reflector of the head light and then re-reflecting said rays of light forwardly and downwardly; the defining of the lateral outlines of the light by the suitable shaping of the outer portions of the parabolic reflector at diametrically opposite sides of the reflector; the forming of flutes or ribs on the inside surface of the lens in an arrangement for suitably directing and spreading the light rays laterally at certain portions of the lens at suitable angles, and also downwardly at other portions of the lens.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, where:

Fig. 1 is a sectional plan view of a head light and lens constructed in accordance with my invention.

Fig. 2 is a vertical sectional view of said head light and lens.

Fig. 3 is a front view of said lens and reflector.

Fig. 4 is a sectional view of said lens, the section being taken on the lines 4—4 of Fig. 3.

Fig. 5 is a fragmental sectional view of the 55 lens 18 at said transverse plane. The ledge 21 is

2

lens, the section being taken on the lines 5—5 of Fig. 3.

Fig. 6 is a sectional view of the lens, the section being taken on lines 6—6 of Fig. 3.

Fig. 7 is a diagrammatic view of the parabolic reflector in the horizontal plane.

Fig. 8 is a diagrammatic view showing the outline of the beam emanating from my head light.

Fig. 9 is a diagrammatic view of the directing of the light rays through a portion of the lens in my head light, and

Fig. 10 is a diagrammatic view showing the directing of the light rays through another portion of said lens.

My head light may be mounted or housed in various types of head light bodies or barrels or housings, therefore in the herein illustration and description, the showing is limited to the reflector and the lens and their connections and cooperation. A reflector 11 is of the usual parabolic mirrored metal providing a parabolic reflector surface. At the center or apex 12 of the reflector 11 is provided a suitable socket 13 to support an electric light or bulb 14 in any suitable manner. The base or open end 16 of the reflector 11 is substantially circular except for two diametrically opposed portions across the horizontal diameter of the reflector base 16. At 30 these vertical portions 17 the periphery of the reflector 11 is raised inwardly so as to provide a curved substantially spherical segment projecting and tapering inwardly of the parabolic reflector to form transversely reflecting surfaces at said areas, as particularly shown in Figs. 1 and 7. These raised areas or surfaces 17 reflect light rays laterally and substantially horizontally so as to widen the beam emanating from the head light.

40 To the open base 16 of the parabolic reflector 11 is secured a lens 18. This lens is made of a transparent material such as glass and it is preferably molded in a concave-convex form. The upper third portion of the lens 18 is formed

45 into a segmental visor portion 19. It is to be understood that the entire lens 18 is in the shape of a segment of a sphere, and the transverse visor portion 19 is also formed in the shape of a spherical segment. The lower edge 50 of the visor segment 19 projects beyond the convex surface of the lens 18 so as to form a ledge 21 across the entire width of the lens 18. This ledge 21 is horizontal and arcuate corresponding to the transverse curvature of the lens 18 at said transverse plane. The ledge 21 is

above the horizontal center plane of the lens 18.

The concave inner surface of the visor segment 19 is mirrored either by direct coating on the surface of said visor segment 19 or by inserting a correspondingly shaped reflector piece fitted into the concavity of said visor segment 19. The radii of the curvatures of the visor segment 19 are struck from a center substantially in front of the focus of the parabolic reflector.

The light rays which emanate upwardly from the light 14 are reflected from the visor segment 19 back to the reflector 11 and then are re-reflected from the parabolic reflector 11 forwardly and downwardly and then out through the lower two thirds of the lens 18.

For the distribution of the light rays both laterally and downwardly, the portion of the lens below the ledge 21 is provided with vertical flutes on its inner surface. The flutes are substantially vertical but are arcuate in conformance with the concave curvature of the inner surface of the lens 18. There are several sets or groups of flutes arranged for the best distribution of light. In the present illustration there are two adjacent flutes 23 extending generally vertically at the vertical center plane of the lens. On each side of each center flute 23 are four vertical flutes 24, each of which is thicker at its upper portion 26 and at its lower portion 27, said upper and lower portions 26 and 27 being of substantially the same thickness. The middle portion of each flute 24 between said thicker portions 26 and 27 is about the same depth or thickness as the two central flutes 23. There are four side flutes 28 between the periphery of the lens and each set of said vertical flutes 24. Said side flutes 28 are slightly arcuate curving downwardly and outwardly toward the periphery of the lens. The central lower portion of the lens 18 is formed into a downward segment by an arcuate ledge 29 and is provided with a plurality of substantially vertical flutes 31 between said arcuate ledge 29 and the lower periphery of the lens 18. These flutes 31 may be in continuation of the adjacent vertical flutes 24 or may be narrower according to the lateral and downward direction required. The direction and spreading of light rays varies according to the dishing of the concave flutes and according to the thickness of the lens at the respective flutes. The middle portions of the vertical flutes 24, the central flutes 23 and the side flutes 28 are of about the same thickness. The upper and lower portions 26 and 27 of the vertical flutes 24 are thicker and project inwardly of the lens 18. The flutes 31 under the arcuate ledge 29 are the thickest and project further inwardly of the lens 18. All the flutes are transversely dished and concave and are also longitudinally dished parallel with the curvature of the lens 18.

The outer periphery of the lens 18 is provided with a suitable annular flange 32 which is engaged by a suitable clamping ring 33 for mounting on the reflector base 16.

The light rays emanating from the source of light, such as the bulb 14, travel in several directions. The light rays which travel toward the inside surface of the parabolic reflector 11 are reflected horizontally forward toward the lens 18. Such of these horizontal rays which are beneath the level of the visor ledge 21 are denoted by the letter A. Certain of the light rays denoted by the letter B travel upward or horizontally in the upper third portion of the lens 18,

and such rays B are reflected from the mirrored visor surface of the visor 19 back to the parabolic reflector 11 downwardly and rearwardly so that they may be re-reflected from the parabolic reflector 11 horizontally to the lens 18 under the level of the visor ledge 21. This reduces upward glare and at the same time intensifies the horizontal light beam through the lower two thirds of the lens 18. As shown in Fig. 7 light rays C which emanate from the light 14 are reflected from the raised vertical portions 17 of the reflector 11 at an angle substantially laterally to the respective opposite sides of the light beam thereby to widen the lateral sweep of the light beam 34 as indicated in Fig. 8.

The arrangement of the flutes on the lower two thirds portion of the lens 18 diffuses and distributes the light rays so as to provide a uniformly intense beam in the shape of the beam 34 as shown in Fig. 8. The light rays directed through the central flutes 23 and through the middle portion of the vertical flutes 24 as well as the side flutes 28 are the least deflected because these are the shallowest or thinnest portions of the lens. On account of the curvature of these flutes there will be a downward direction of such of the light rays which are reflected downwardly toward the lower portions of these flutes. The spread of the light rays passing through the thicker flute portions 26 and 27 is greater because of the increased thickness of the lens and of the increased spreading and diffusing action of these thicker portions of the flutes. The downward as well as the lateral direction of the light rays is the greatest at the thickest portions of the lens between the arcuate ledge 29 and the lower middle periphery of the lens 18. This provides for a greater intensity of downward and lateral illumination in the portions of the beam 34 closest to the ground. The flutes being cross-sectionally arcuate on the inner surface will direct the rays of light differently in each flute according to whether the rays of light enter through the shallowest cross sectional portion of each flute or through the thickest arcuate side of each flute. The arrangement and proportioning of the flutes and their thicknesses on the inner surface of the lens 18 is such that there is no glaring central portion in the light beam 34 but there is a substantially uniform distribution of light through the width and height of the light beam 34 issuing from the head light.

I claim:

1. In a lens for a head light, a reflector visor formed integrally across an upper portion of said lens, a plurality of parallel flutes extended downwardly from said visor to the lower periphery of said lens, portions of said flutes on spaced areas on said lens being thicker than other portions of said flutes for direction of light rays at different angles than other portions of said flutes, said thicker flute portions being arranged substantially symmetrically about the middle of the lower portion of said lens, an arcuate ledge formed near the lowest portion of the periphery of the lens to confine a downwardly directing area, a plurality of flutes in said area, the lens at said area being thicker than the thickness at all the other flutes.

2. In a lens for a head light, a reflector visor formed integrally across an upper portion of said lens, a plurality of parallel flutes extended downwardly from said visor to the lower periphery of said lens, portions of said flutes on spaced areas on said lens being thicker than other portions of

said flutes for direction of light rays at different angles than at other portions of said flutes, said thicker flute portions being arranged substantially symmetrically about the middle of the lower portion of said lens, an arcuate ledge formed near the lowest portion of the periphery of the lens to confine a downwardly directing area, a plurality of flutes in said area, said area being thicker than the thickness of all the other flutes, each of said flutes being transversely arcuate on the concave face of said lens. 10

JACK CATHRILL.
